US0D1001876S

(12) **United States Design Patent** (10) **Patent No.:** **US D1,001,876 S**
Drost (45) **Date of Patent:** **** Oct. 17, 2023**

(54) **ENCLOSURE FOR CAPTURE DEVICES**

(71) Applicant: **Musco Corporation**, Oskaloosa, IA (US)

(72) Inventor: **Matthew D. Drost**, Oskaloosa, IA (US)

(73) Assignee: **Musco Corporation**, Oskaloosa, IA (US)

(**) Term: **15 Years**

(21) Appl. No.: **29/720,929**

(22) Filed: **Jan. 16, 2020**

(51) **LOC (14) Cl.** **16-05**

(52) **U.S. Cl.** **USPC** **D16/242**

(58) **Field of Classification Search**

(57) **CLAIM**

The ornamental design for an ENCLOSURE FOR CAPTURE DEVICES as shown and described.

DESCRIPTION

FIG. 1 is a perspective view of the ENCLOSURE FOR CAPTURE DEVICES in a first configuration;
FIG. 2 is a front elevation of FIG. 1;
FIG. 3 is a back elevation of FIG. 1;
FIG. 4 is a right side elevation of FIG. 1;
FIG. 5 is a left side elevation of FIG. 1;
FIG. 6 is a top plan view of FIG. 1;
FIG. 7 is a bottom plan view of FIG. 1;
FIG. 8 is a perspective view of the ENCLOSURE FOR CAPTURE DEVICES in a second configuration;
FIG. 9 is a front elevation of FIG. 8;
FIG. 10 is a back elevation of FIG. 8;
FIG. 11 is a right side elevation of FIG. 8;
FIG. 12 is a left side elevation of FIG. 8;
FIG. 13 is a top plan view of FIG. 8; and
FIG. 14 is a bottom plan view of FIG. 8.
The broken lines shown in the drawings illustrate portions of the ENCLOSURE FOR CAPTURE DEVICES that form no part of the claimed design.

1 Claim, 14 Drawing Sheets
